COMMUTATOR PLATE

George J. Lynch, Bloomfield, N. J., assignor to Mycalex
Electronics Corporation, Clifton, N. J., a corporation
of New York

Application April 27, 1956, Serial No. 41,239

Term of patent 14 years

(Cl. D26—13)

Fig. 1.

Figure 1 is a front elevational view of a commutator plate embodying my new design;

Figure 2 is a rear elevational view of the commutator plate shown in Figure 1; and

Figure 3 is a side elevation view of said commutator plate.

I claim:

The ornamental design for a commutator plate, substantially as shown.
